UNITED STATES PATENT OFFICE.

CARMELO CAMMARATA, OF UNIONTOWN, PENNSYLVANIA.

LINE-HOLDER.

1,055,019.

Specification of Letters Patent.

Patented Mar. 4, 1913.

Application filed August 17, 1912. Serial No. 715,643.

To all whom it may concern:

Be it known that I, CARMELO CAMMARATA, a native of Italy, subject of King Victor Emmanuel III, residing at Uniontown, in the county of Fayette and State of Pennsylvania, have invented certain new and useful Improvements in Line-Holders, of which the following is a specification, reference being had to the accompanying drawings.

10 This invention comprehends certain new and useful improvements in line holders for use by brick-layers and those engaged in similar vocations to assist in properly laying out their work, and the invention has for 15 its primary object a simple, durable and efficient construction of device of this character which will securely hold a line and properly retain the same in position without the necessity of using nails or similar 20 devices for maintaining the end of the line at the desired point.

The invention also has for its object a simple device of this character provided with improved means whereby the line end 25 may be securely fastened to it at different required adjustments, according to the length of line required, and which will be so formed that the line may be easily fastened thereto and disconnected therefrom, 30 as desired.

A further object of the invention is a device of this character provided with improved means, whereby it may be securely held in place and prevented from tipping, 35 when the line is secured at the topmost course of the bricks or blocks. And the invention also aims to generally improve devices of this class and to render them more useful and commercially desirable.

40 With these and other objects in view, as will more fully appear as the description proceeds, the invention consists in certain constructions, arrangements and combinations of the parts that I shall hereinafter 45 fully describe and claim.

For a full understanding of the invention, reference is to be had to the following description and accompanying drawing, in which,

50 Figure 1 is a side elevation showing my improved line holder in applied position. Fig. 2 is a perspective view of one of the holders with the end of a line secured thereto. Fig. 3 is a transverse sectional view 55 through one of the holders. Fig. 4 is a side elevation of the complementary holders when

nested or arranged in abutting relation to each other for convenience in carrying in the pocket or stowing away in the kit, and Fig. 5 is an inner face view of one of the holders 60 showing the manner of using the same at the topmost course of the work.

Corresponding and like parts are referred to in the following description and designated in the accompanying drawing by like 65 reference characters.

Each of my improved line holders comprises a body portion 1 formed with an extension 2 which produces a shoulder 3. The body portion 1 is provided at one end with a curved recess 4 and with inwardly extending tapering recesses 5 in which the line 6 is adapted to be passed so as to securely fasten the line to the holder.

7 designates the end of the line which, as 75 will be best illustrated in Figs. 1 and 2, is passed into the middle one of the recesses 5, at the required point, according to the length of line desired, and is then passed one or more times through the recesses 5, thereby 80 holding the line taut and under the required tension. The extension 2 of the body portion 1 is formed in its face adjoining the shoulder 3, with a groove 9 which communicates at one end with the opening 8 extending 85 through the extension at the juncture thereof with the main part of the body portion, the line being passed through the opening 8 and lying along the groove 9, whereby it will be substantially flush with the face 90 of the extension.

From as much of the description as has preceded, in connection with the correlated views of the accompanying drawing, it will be understood that in the practical application or use of my improved line holders, one of them is secured to each end of the line, the line being adjusted and fastened to one end of the holder, according to the length of line desired, and the holders being disposed vertically on the partially built up corners of the building structure with the shoulders 3 extending around the sides of the structure, as clearly indicated in Fig. 1. As the work progresses, it is 100 manifest that the line holders are slipped upwardly, whereby they will at all times serve as a guide or gage for laying the intermediate bricks of the respective courses, and it will be seen that by the use of a device 105 such as I have invented, it is not necessary to use nails or similar fastening devices to

fasten the line to the wall, but it is only necessary to adjust the line to the holders and to then stretch the line taut, so that the shoulders 3 of the holders will extend 5 around the sides of the bricks. When not in use, the pair of holders may be mated with each other, as clearly illustrated in Fig. 4, and the line wound around them, the recesses 4 in which the line is wound, preventing the line from slipping sidewise from the holders and become tangled and permitting the holders to come apart.

In order to prevent the holders from tipping, when laying the top course, I provide 15 them with spurs 9' pivotally connected at one end to the body portion 1 and adapted to be swung out beyond the shoulders 3 so as to engage the corner bricks, as clearly indicated in Fig. 5, whereby all tipping of 20 the holders and the consequent throwing of the line out of position, is positively precluded. In their operative positions, the spurs 9' are disposed obliquely beyond the shoulders 3 and are limited to such position 25 by pins 10 engaging in notches 11 formed in the edges of the spurs. In this position of the spurs, their lower free edges are on a line with the grooves 9 and consequently, the line 6.

30 While the accompanying drawing illustrates what I believe to be the preferred embodiment of my invention, it will be understood that various changes may be made in the construction, arrangement and proportions of the parts without departing 35 from the scope of the invention, as defined in the appended claims.

What I claim is:—

1. A line holder, comprising a body portion 40 formed with an extension and a shoulder adjoining one face of the extension, a leveling spur pivotally secured to the side of the body portion and movable outwardly beyond said shoulder in a plane parallel to the said side and to the said face of the extension, and means for limiting movement of the spur upon its pivot.

2. A line holder, comprising a body portion 50 formed with an extension and a shoulder adjoining one face of the extension, a leveling and bracing spur connected to one side of the body portion and movable outwardly beyond said shoulder in a plane parallel with the said face of the extension for engagement upon the work to level and brace the holder, such face of the extension being formed with a longitudinal groove, and means for limiting the movement of the spur in one direction at a point where one

end of the spur will be in line with said 60 groove and upon the work, for the purpose specified.

3. A line holder for position at the upper corner of a wall, said holder comprising a body portion and an extension for engagement with the corner of the wall, a leveling and bracing spur pivoted to one face of the extension and adapted for engagement upon the top of the wall, means for limiting the pivotal movement of the spur, and means 70 for securing one end of the line to the holder.

4. A line holder comprising a body portion formed with an extension and adapted for engagement with the corner of the wall, 75 a spur pivoted to one face of the extension and adapted for engagement with the top of the wall to level and brace the holder, the end of the extension being provided with a plurality of slots to form spaced 80 blocks adapted to have wound therearound the end of a line to hold the latter, and means for limiting the pivotal movement of the spur and retaining the same in engagement with the top of the wall. 85

5. A line holder comprising a body portion formed with an extension adapted for engagement against the right angled walls of a structure at the corner thereof, the extension having a curved face with a plurality of slots extending inwardly therefrom to receive the end of a line and also to produce spaced wedge blocks around which the line may be engaged, a spur carried by one face of the extension and adapted for engagement against the wall to support the holder in proper position at the corner of the structure. 90

6. A line holder comprising a body portion formed with an extension and adapted 100 for engagement with the corner of a structure, said body portion having a line extending therefrom, means carried by the extension for holding the end of the line, a bracing spur carried by the extension and having its upper end adapted for engagement against the top of the structure and in alignment with the line to brace the holder and retain the same in position against the corner of the structure, and means for locking 105 the spur in position.

In testimony whereof I hereunto affix my signature in the presence of two witnesses.

CARMELO CAMMARATA.
